UNITED STATES PATENT OFFICE.

EDSON R. WOLCOTT, OF PORT ARTHUR, TEXAS.

BURNER FOR HEAVY HYDROCARBONS.

Application filed December 20, 1923. Serial No. 681,851.

This invention relates to means for burning crude petroleum, petroleum residue, or other heavy hydrocarbons which tend to decompose on burning, with resulting incomplete combustion, and formation of considerable free carbon, and the main object of the invention is to provide for substantially complete and effective combustion of such heavy hydrocarbons. A further object of 10 the invention is to provide an oil burner which will first separate the more volatile from the less volatile constituents of the hydrocarbons and will burn such constituents separately so as to provide for the most effective combustion of each of said constituents. A further object of the invention is to utilize heat developing by the combustion of the most volatile and more readily combustible of the hydrocarbons for ensuring combustion of the carbon and less volatile hydrocarbons.

The accompanying drawings illustrate an embodiment of my invention and referring thereto:

Fig. 1 is a vertical section of the oil burner, and Fig. 2 is a horizontal section on line 2—2 in Fig. 1.

Fig. 3 is a vertical section of the lower portion of the oil burner showing a modified form of the refractory body therein.

Fig. 4 is a sectional view of a portion of a furnace showing my burner as applied thereto.

My improved oil burner may comprise oil supply means consisting of a pipe 1 connected to any suitable source of crude oil or other heavy hydrocarbon and having an outlet tube 2 provided with regulating valve 3, said outlet tube opening into a heating chamber or volatilizing chamber 4 formed for example as a vertical tubular chamber closed at the top and tapering at its lower end to an outlet opening 5. Below said outlet opening 5 I provide means for receiving unvolatilized carbonaceous material and exposing the same so as to permit combustion thereof, said means consisting for example of a body of refractory material which preferably consists of porous or perforate fire clay, silica brick or other similar material either in the form of checker work 6 as in Fig. 1 or in the form of fragments 6' disposed so as to form interstices for the passage of air therethrough as shown in Fig. 3, the said mass being mounted on a suitable support such as a tubular member

7 provided if necessary with a grate on which the porous or perforate mass rests.

The refractory mass above referred to constitutes a burner means for receiving and exposing the carbonaceous residuum to combustion, and means are provided for conducting to this burner means, volatile hydrocarbons such as gas or vapor produced by volatilization of the supplied crude oil or heavy hydrocarbon in the heating or volatilizing chamber 4. For this purpose one or more pipes indicated at 8 may lead from said volatilizing chamber 4 to a burner or burners 9 adjacent to the tubular support 7 and are provided with any desired number of orifices 10 extending in or adjacent to the refractory burner body 6. Air inlets 11 may be provided for addition of air to the gases or vapors so supplied, such air being preferably mixed with the gases or vapors before they reach the point of combustion so as to provide for more effective combustion.

The burner above described is enclosed in a suitable combustion chamber indicated at 14, having inlet 15 at its bottom for air and outlet 16 at its top for products of combustion, this combustion chamber confining the products of combustion and conducting them to the said outlet.

The operation of the burner is as follows:

The crude oil or other heavy hydrocarbon leaves the supply pipe or tube 2 at a point which is not sufficiently heated to form coke at such outlet point, the outlet of said tube 2 being preferably tapered so as to cause the oil to fall in drops which pass through the chamber 4. Said chamber is heated by the outgoing gas or products of combustion so that the drops of oil in falling through said chamber are heated sufficiently to volatilize the lighter constituents, forming gas or vapor which passes down through the pipes 8 to the burner chamber 9 wherein such gas or vapor is mixed with air and burns at or adjacent to the burner means 6. Movement of the volatilized gas or vapor to the burner from the chamber 4 is effected by the ejection effect of the burner and by the vapor pressure in chamber 4. The residuum of the oil, consisting of the non-volatile or unvolatilized portions of the hydrocarbon including any free carbon which may be formed, falls freely and continually through outlet opening 5 and is received on the burner means 6 directly below said opening and is burned thereon by combustion with the air entering

2

through the tubular support 7 and through the refractory mass constituting the burner means 6, the heat furnished by the gas flame from burner 9 aiding in maintaining and 5 ensuring complete combustion of such residual material. The hot products of combustion from both the volatile and non-volatile portions of the hydrocarbon pass upwardly around the volatilizing chamber 4 so as to heat the same as above described and 10 pass out through the outlet 16. It should be noted that the outlet 2 of the supply means is directly above the opening 5 at the lower end of the volatilizing chamber and the 15 burner means 6 is directly below said opening. The heavy liquid hydrocarbon is continually supplied, preferably in the form of drops, to the upper portion of the volatilizing chamber and in falling therethrough the 20 volatile portions are volatilized by the heat in said chamber, while the unvolatilized portion falls freely and continually through opening 5 onto burner means 6.

By the above described means it is possible to burn crude oil or heavy residuum with substantially complete combustion. The invention provides means for removing the gaseous or volatile hydrocarbons and burning them in such portion that the heat 30 from such combustion aids in the combustion of the heavy residuum and on the other hand such residuum is burnt at a point outside of the volatilizing chamber so that there is no danger of clogging the volatilizing chamber.

To start the burner, a porous refractory filled with kerosene would be inserted between the two gas burners and left there until the refractory and contained coke became red hot.

I have indicated in Fig. 1 an outlet for the hot products of combustion, it being understood that this outlet may lead to any suitable heat utilizing means. It will be understood however, that the oil burners described may be positioned directly below or adjacent to the means to be heated, for example, the oil burners may be enclosed in a suitable fire box or combustion chamber 14 forming part of a furnace 17, as shown in Fig. 4.

While this invention is particularly adapted to the combustion of heavy hydrocarbons it is not intended to limit its use thereto as it may also be used to advantage with lighter hydrocarbons.

What I claim is:

1. A hydrocarbon burner comprising supply means for liquid hydrocarbon, a volatilizing chamber adapted to receive such liquid hydrocarbon from said supply means and provided at its lower end with an opening adapted to permit free and continual discharge of residual material, a burner means positioned directly below said lower open-

ing of the volatilizing chamber and adapted to receive the residual hydrocarbon therefrom, means for conducting to said burner means hydrocarbon vapor produced by action of heat on the hydrocarbons supplied to the said volatilizing chamber, said burner means being provided with means for supplying air thereto for combustion of both the residual hydrocarbon and the said hydrocarbon vapor and means for conducting the hot products of combustion from said burner means to a position to heat the said volatilizing chamber.

2. A burner for heavy liquid hydrocarbons comprising a volatilizing chamber having an opening at its lower end; means for continually supplying liquid hydrocarbon to the upper portion of said volatilizing chamber, a burner means positioned below said opening at the lower end of said volatilizing chamber so as to receive residual liquid hydrocarbon passing through said volatilizing chamber, means for conducting to said burner means hydrocarbon vapor produced by the action of heat on the liquid hydrocarbon in the volatilizing chamber, said burner means being provided with means for supplying air thereto for combustion of both residual hydrocarbon and said hydrocarbon vapor, and means for conducting the hot products of combustion from said burner means to position to heat the said volatilizing chamber.

3. A burner for heavy liquid hydrocarbons comprising a vertical tubular volatilizing chamber, means for continually introducing liquid hydrocarbon into the upper end of said volatilizing chamber so as to cause said liquid hydrocarbon to fall through said volatilizing chamber and permit volatile portions of such hydrocarbon to be volatilized by the heat in said volatilizing chamber, said volatilizing chamber having an opening at its lower end to permit free and continual passage therethrough of unvolatilized portions of the hydrocarbon, burner means located directly below said opening at the lower end of said volatilizing chamber so as to receive such unvolatilized hydrocarbon passing through said opening, means for conducting vaporized portions of the hydrocarbon from the upper end of said volatilizing chamber to said burner means, means for supplying air to said burner means for combustion of the un-vaporized and vaporized portions of the hydrocarbon, and means for conducting the hot products of combustion from said burner means to position to heat said volatilizing chamber.

4. A burner for heavy liquid hydrocarbons comprising a vertical tubular volatilizing chamber provided at its lower end with an opening, means for continually supplying liquid hydrocarbon in the form of drops to the upper portion of said volatilizing cham-

- ber so as to cause such drops to fall through said chamber and permit volatile portions thereof to be volatilized by the heat in said volatilizing chamber, said liquid hydrocarbon supply means being located directly above said opening so as to permit unvolatilized portions of the hydrocarbon to fall freely through said opening, burner means located directly below said opening to receive such unvolatilized hydrocarbon, means for conducting volatilized hydrocarbon from the upper end of said volatilizing chamber to said burner means, means for supplying air to said burner means for combustion of the volatilized and unvolatilized portions of the hydrocarbon and means for conducting hot products of combustion from the burner means to position to heat said volatilizing chamber.
5. A burner for heavy liquid hydrocarbons comprising a vertical tubular volatilizing chamber having an opening at its lower end, means for supplying liquid hydrocarbon to the upper end of said volatilizing chamber and directly above said opening so as to cause such hydrocarbon to fall through said volatilizing chamber and permit volatilization of volatile portions thereof by the heat in said chamber, burner means located directly below the opening at the lower end of said volatilizing chamber and adapted to receive unvolatilized portions of the hydrocarbon passing through said opening, burner means located adjacent said first-named burner means, means for conducting volatilized hydrocarbon from the upper end of said volatilizing chamber to said second-named burner means, means for supplying air to both of said burner means for combustion of the hydrocarbon supplied thereto and means for conducting hot products of combustion from both of said burner means in position to heat said volatilizing chamber.
10. In testimony whereof I have hereunto subscribed my name this 17th day of December 1923.
15. 20. 25. 30. 35. 40. 45.

EDSON R. WOLCOTT.
